UNITED STATES PATENT OFFICE.

JOHN THOMAS BATTs, OF GRAND RAPIDS, MICHIGAN.

DESIGN FOR A COSTUMER STAND.

60,639.

Specification for Design. Patented Mar. 21, 1922.

Application filed January 3, 1921. Serial No. 434,802. Term of patent 3½ years.

To all whom it may concern:

Be it known that I, JOHN THOMAS BATTs, a citizen of the United States, residing at the city of Grand Rapids, in the county of Kent and State of Michigan, have invented a new, original, and ornamental Design for a Costumer Stand, of which the following is a specification, reference being had to the accompanying drawing, forming a part thereof.

The figure is an elevation of the costumer stand, showing my new design.

I claim:

The ornamental design for a costumer stand, substantially as shown.

In testimony whereof, I heunto affix my signature.

JOHN THOMAS BATTs.
